UNITED STATES PATENT OFFICE.

ANDREAS B. ANDREASSEN, OF BROOKLYN, NEW YORK.

LIFE-BOAT.

1,080,876.

Specification of Letters Patent.

Patented Dec. 9, 1913.

Application filed August 26, 1912. Serial No. 717,080.

To all whom it may concern:

Be it known that I, ANDREAS B. ANDREASSEN, a subject of the King of Norway, residing at 7210 Third avenue, Brooklyn, in the county of Kings and State of New York, have invented certain new and useful Improvements in Life-Boats, of which the following is a specification.

This invention relates to that class of boats which are employed for saving human lives from sinking on wrecked vessels.

It is the object of the present invention to provide a boat of the kind stated, which is safe and able to withstand rough weather, and which is easily controlled.

The invention also has for its object to provide a boat having great stability, the same being obtained by a novel arrangement of compartments and ballast.

Other objects and advantages of the invention will be pointed out in the detailed description appearing hereinafter.

In order that the invention may be better understood, reference is had to the accompanying drawing, in which—

Figure 1 is a longitudinal section of the forward half of the boat. Fig. 2 is a similar view of the rear half thereof. Fig. 3 is a horizontal section on the line 3—3 of Fig. 1. Fig. 4 is a horizontal section on the line 4—4 of Fig. 2. Fig. 5 is a transverse section on the line 5—5 of Fig. 1. Fig. 6 is a similar view on the line 6—6 of Fig. 2.

In the drawings 10 denotes the hull of the boat, the same having a double bottom and transverse bulkheads 11, whereby a number of transverse water-ballast compartments 12 are produced in the bottom of the hull. At the bow and stern of the hull are air-tight compartments 13 and 14, respectively, and in the hull, along both sides thereof, are seats 15, below which are air-tight compartments 16. The compartments 12 are provided with man-holes which have covers 17.

The hull is closed over by a top 18 having side doors 19 through which the crew and passengers enter and leave the boat. The hull and top are braced by ribs 20 extending around the same on the inside thereof.

In the forward part of the hull, on the port side, suitably partitioned off, is located a closet 21 which is flushed by a pipe 22 extending transversely through the forward

compartment 12, and opening at its ends through the sides of the hull, below the water line. Each end of this pipe contains a valve 23.

The boat is provided with a screw propeller 24 and a rudder 25. The propeller is driven by a manually operated gearing 26 located in the aft part of the hull. The rudder is operated from a steering wheel 27 located forward in the hull, from which lines 28 run to the tiller 29.

The gearing 26 is also connected to pumps 30 having suction pipes 31 extending into a well 32. Suitable means will be provided for disconnecting the pumps from the drive gearing 26.

The compartments 13 and 14 may be used for holding provisions and other stores, and the compartments 12 carry a ballast of fresh water which will be replenished by sea water when used up. In order that this may be conveniently done there is provided a pipe 33 extending along the bottom of the hull, on the inside thereof, and having branches 34 which are connected to the respective compartments 12, and contain valves 35. One end of the pipe 33 is connected to the pipe 22 so that the compartments may be filled with sea water for ballast. The pipe 33 has a valve 36 controlling the flow thereinto from the pipe 22. The other end of the pipe 33 is connected to the pumps 30 in order that the ballast may be pumped out. A pipe 37 is also in communication, by means of branches 38, with the respective compartments 12, said branches having valves 39. This pipe leads to a hand pump 40 for withdrawing fresh water from the compartments.

In the bow of the boat is located an oil tank 41 from which lead pipes 42, the latter opening through the sides of the hull for sprinkling oil on the water. A similar tank 43 and discharge pipes 44 are located at the stern of the boat.

The top 18 has ventilators 45 provided with closures 46. The ventilators are swiveled so that they may be turned in any direction, and the closures are adapted to be controlled simultaneously by a longitudinally slideable bar 47 which is operatively connected by a series of jointed rods to the respective closures. As shown three connecting rods are provided for each closure, one of the rods 48 is pivoted at 48^a to the bar 47 and another rod 48^b is connected to

the closure, whereas another rod 48^c is slidably mounted in and guided by cross bars 48^d inside the ventilator. The last mentioned rod is swiveled at one end as indicated at 48^e to the rod 48^b and at its other end it is connected by a ball-and-socket joint 48^f to the rod 48. It will be evident that the herein described jointed rod connection between the bar 47 and the closures enables 10 the ventilators to be swung around as stated without affecting the operation of the closures. The bars 47 are supported by guides 49, and to one end of said bars is connected an operating lever 49^a provided with a suitable locking device 49^b. As shown in Figs. 5 and 6 two rows of ventilators are provided.

In the sides of the top 18 and on the front thereof are port holes 50 which show red 20 and green on proper sides so that side lights may be placed therein. In the top 18, at the forward part thereof is mounted a tubular upright 51 which contains properly colored signal lamps 52. The upright is movable 25 vertically so that it may be lowered into the boat when not in use, as shown by dotted lines in Fig. 1. Through the upright 51 extend two tubes 53 and 54, respectively, which pass down into the boat and open 30 through the top of the upright. The tube 53 is for receiving and conducting sound from the outside when the boat is closed up. The tube 54 leads to a siren or fog horn 55. The upright also carries a compass (not 35 shown). The top 18 also carries an aft tubular upright 56 for a stern light 57, and in the day time said upright serves as a support for the pole of a flag.

In the bottom of the hull are sounding 40 pipes 58.

All doors and port hole covers will be constructed so as to make a water-tight closure.

The boat also contains hoisting devices 59 which are employed for launching purposes. The launching apparatus is shown 45 and claimed in a companion application.

In the forward part of the hull, on the starboard side is a locker 60.

A boat constructed as herein described is safe in all kinds of weather and affords 50 ample and comfortable accommodation for a large number of passengers. In rough weather the boat can be entirely closed up. The various compartments impart stability to the boat, there is no danger of the boat 55 upsetting, and the interior arrangement enables the boat to be easily controlled.

The preferred embodiment of the invention has been shown, but it will be understood that various changes in the structural 60 details may be made without a departure from the spirit and scope of the invention.

I claim:

1. A boat having a hull provided with transverse bottom compartments for water 65 ballast, a pipe passing through one of the compartments and opening through the sides of the hull below the water line, a pipe connected to said pipe, a valve for shutting off and establishing communication between 70 said pipes, the second-mentioned pipe having branches extending respectively into the transverse compartments, a valve in each of said branches, and a pump having its inlet connected to the second-mentioned pipe. 75

2. A boat having a hull provided with transverse bottom compartments for water ballast, a pipe passing through one of the compartments and opening through the sides of the hull below the water line, a 80 pipe connected to said pipe, a valve for shutting off and establishing communication between said pipes, the second-mentioned pipe having branches extending respectively into the transverse compartments, a valve 85 in each of said branches, a pump having its inlet connected to the second-mentioned pipe, and a second pump connected to the compartments for emptying the same.

In testimony whereof I affix my signature 90 in presence of two witnesses.

ANDREAS B. ANDREASSEN.
